UNITED STATES PATENT OFFICE.

DOMINICK FRANOVICH, OF VENICE, LOUISIANA.

DRY DOCK.

Application filed January 13, 1922. Serial No. 529,061.

To all whom it may concern:

Be it known that I, DOMINICK FRANOVICH, a citizen of the United States, residing at Venice, in the parish of Plaquemines 5 and State of Louisiana, have invented new and useful Improvements in Dry Docks, of which the following is a specification.

My present invention pertains to dry docks, and it contemplates the provision of 10 a dock through the medium of which ship workers may be enabled to work in an up-standing position at all times irrespective of the location of the repairs to be made to the ship.

15 The invention further contemplates the provision of a dock through the medium of which the ship to be repaired may be quickly and easily tilted to various positions to assure the workman obtaining access to the 20 various parts of the hull of a ship; to position the ship so as the light will be properly thrown on the hull thereby relieving strain on the workers' eyes, and to overcome injury to workmen due to inaccessibility of various parts of the ship's hull.

The invention further contemplates the provision of a dock that will enable the work of repair on a ship being carried on in an efficient and speedy manner without attending 30 danger to life and limb of the ship-workmen.

The invention in all of its details will be 35 fully understood from the following description and claims when the same are read in connection with the drawings accompanying and forming part of this specification, in which:

Figure 1 is a top plan view of my novel 40 dock positioned on its complementary base or platform.

Figure 2 is a side elevation of the dock shown in Figure 1.

Figure 3 is a front elevation of the device 45 with the cradle and ship shown in upright position.

Figure 4 is a view showing the cradle and ship in tilted position with respect to the dock.

Figure 5 is a view showing the cradle 50 position of the dock in extended position.

Similar numerals of reference designate corresponding parts in all the views of the drawings.

55 My novel dock comprises the base portion composed of the side bars 1 that are secured to each other by means of the cross-bars 2

and the said bars or rails 1 are provided in their upper face with longitudinal tracks or channels 3. The platform or base so far described is adapted to be positioned in any 60 form of berth B as shown in Figure 3.

My novel cradle dock comprises the front and rear members 4 that are secured to each other by means of the telescoping rods or rails 5 and 6. The rods 5 are secured to one 65 of the members 4 and the rods 6 are secured to the other of the members 4 and are adapted to enter the rods 5 whereby the members 4 are longitudinally adjustable with respect to each other.

The members 4 are provided with the legs or portions on their lower surface, that travel in the tracks or channels 3 of the rods or rails 1 of the base of the dock, and the members 4 are also provided with the 75 integral upstanding portions 7 that are provided in their upper face with the channel 8 that receive the tongue 9 of the members 10 of cradle C. The members 10 like the members 7 are of semi-circular form in front elevation, and are adapted to have their tongues 9 travel to right and left in the channels 8 during rocking movement of members 10, and secured to the cradle members 10 are the hull receiving brace members 80 11 clearly shown in Figures 3 and 4. The cradle members 10 and members 11 are integral with each other and secured to the one member 11 on each side thereof are rods 12. The opposite member 11 is provided with 90 rods 13 that enter the rods 12 of the opposing member 11 and hence the cradle C are adjustable longitudinally with respect to each other after the manner of the members 4 to accommodate the cradle to various 95 lengths of ships.

On the upper ends of the cradle C I provide hooks 14 to receive the rods 14^a that are in turn secured to the ship A. This provision is made in order to hold the ship with 100 respect to the cradle C during the tilting operation.

On the outer face of the members 4, I provide the windlasses 15 that are provided with the cables 15^a that rest beneath the cradle C. By manipulation of the windlass of the members 4 the cradle will be rocked or tilted with respect to the members or dock 4.

Mounted on the rear extension of the dock of my device as shown in Figure 2 are windlasses 16 and 22 that operate the cables to extend and close the dock longitudinally.

2
 The cables 17 are secured to hooks fastened to the rear member 4 and thence over windlass 16. The cables 19 pass over pulley 20 fast to the front cross-bar 2 and is secured to hook 21 that is arranged on one face of member 4 to which the pulley 18 is secured.

10 The cable 23 is secured to one member 24 by means of the hook shown and passes over the windlass 22 and said cable 23 is fast to member 4 by hook 27 and passes from pulley 26 to windlass 22.

15 In the practical use of the invention, the dock members 4 may be positioned near or away from each other by turning the windlasses 16 and 22, to cause telescoping of the rods 5 and 6 and 12 and 13. The ship is then run into the cradle and the entire dock elevated by any means that may suggest itself. 20 The ship is secured to the hooks 14 by the rods 14 and by manipulation of windlass 15 the cradle C as well as the ship A may be tilted to any desired angle with respect to the dock and foundation.

25 The dock described will permit a workman to gain easy access to the hull of the ship without fear of injury and the ship and cradle may be tilted at an angle with a small amount of effort on the part of the workmen. Moreover, because of the provision of the telescoping rods the device is well adapted to accommodate ships of various lengths without alterations.

30 The construction of the dock and base as well as the groove rails 1 assures easy extension and telescoping of the dock with respect to the base when desired.

35 Having described my invention, what I claim and desire to secure by Letters-Patent 40 is,—

45 1. In a dry-dock, the combination of a support, a ship-receiving dock arranged on the support and means for moving the front and rear portions of the dock longitudinally with respect to each other and on the support and other means for rocking a portion of the dock transversely with respect to the support.

50 2. In a dry-dock, the combination of a support, channels formed longitudinally in the rails of the support, a ship-receiving dock mounted on the support and resting in the channels thereof, members for receiving the ship and hooks and rods for holding the ship to said members, telescoping rods se-

cured to the members, a channel in which the members travel and means for causing the rods to telescope and bring the members toward each other, other means for causing the members to move away from each other and a third means for rocking the members transversely on the ship-receiving means.

3. In a dry-dock, the combination of a base, a frame mounted on the base, channels formed in the frame, members having a rail that enters the channel of the frame, means for moving the members with respect to the frame and other means secured to the frame and members for moving each complementary frame and member with respect to its opposing member.

4. In a device for the purpose set forth, the combination of a support, a frame mounted on the support, a rod secured to the frame, a second frame arranged in rear of the first named frame and having a rod in which the rod of the first named frame telescopes, cables secured to the frames, a windlass secured to the support and adapted to move the frames on the support to cause telescoping of the rods or vice versa, ship receiving cradles having a rail that enters a channel formed in each of the frames and a series of windlasses and cables secured to the frames and adapted to rock the cradle from left to right with respect to the frames.

5. In a device for the purpose set forth, the combination of upstanding frames, channels formed in the frames telescoping rods secured to the frames to permit of movement of the frames away from or toward each other, cradles having a portion that receives a ship and provided at their undersides with a tongue that seats in the channels of the frames and means for retaining the cradles with respect to each other and comprising telescoping rods, means arranged on the frames for imparting a rocking movement of the cradles with respect to the frames and other means for telescoping and extending the rods.

In testimony whereof I have hereunto set my hand in presence of two subscribing witnesses.

DOMINICK FRANOVICH.
